UNITED STATES PATENT OFFICE.

GEORGE V. PADE AND CONRAD T. NEITZEL, OF DALLAS, TEXAS, ASSIGNEES TO AMERICAN ART NEEDLE COMPANY, OF DALLAS, TEXAS, A CORPORATION OF DELAWARE.

EMBROIDERY-NEEDLE.

1,371,976.

Specification of Letters Patent. Patented Mar. 15, 1921.

Application filed August 4, 1919. Serial No. 315,055.

To all whom it may concern:

Be it known that we, GEORGE V. PADE and CONRAD T. NEITZEL, citizens of the United States, residing at Dallas, in the county of Dallas and State of Texas, have invented certain new and useful Improvements in Embroidery-Needles, of which the following is a specification.

This invention relates to certain new and useful improvements in embroidery needles, and pertains more particularly to an improvement upon Letters Patent No. 1309601 issued July 8, 1919.

The primary object of the invention is to provide an improved and simplified form of guide and to further form the needle proper so that the latter will be devoid of projections or the like and will possess a handle that is of substantially continuous cylindrical form so as to afford a comfortable grip for the hand of the user and to also facilitate use of the needle.

In the drawings:—

Figure 1, is a side elevation of the invention:

Fig. 2, is a top plan view:

Fig. 3, is a bottom plan view:

Fig. 4, is a detail perspective view of the gage detached from the needle:

Fig. 5, is an enlarged section on line 5—5 of Fig. 3 and

Fig. 6, is a fragmentary view of the needle showing the manner of operation.

In proceeding in accordance with the present invention the needle is formed with a hollow body bent or shaped to form a substantially cylindrical handle 1, with an attenuated shank 2, terminating in a point 3. The side edges of the body are spaced apart to provide a thread-receiving slit 4, which extends from end to end of the needle, while the side edges 5 defining the slit of the handle are given a converging formation as depicted in Fig. 5, to form a guide for the thread in placing the latter interiorly of the hollow needle.

The edges 5, it will be seen are disposed interiorly of the periphery of the handle, so that the handle periphery is left smooth and possessed of a substantially continuous and uninterrupted cylindrical contour devoid of outward projections or the like.

The invention further proposes an improved and simplified gage and means for adjustably mounting same on the needle

body and accordingly a somewhat strip-like section 6 of spring metal is employed provided intermediate its ends with a pair of outwardly curved and opposed spring gripping fingers 7 which latter yieldingly embrace the handle 1, at diametrically opposite points thereon. The forward end of the gage body is formed with an out-turned bifurcated or forked part 8 which straddles the needle point 3, while the opposite end is also turned outwardly and in the same general direction as part 8, to form a pawl 9, which selectively is received in any desired one of a series of transverse notches or openings 10 formed in the handle 1.

The notches are formed in the periphery of the handle 1, at points in the bottom thereof diametrically opposite the slot 4, and since the pawl 9 is formed of an extension of an end of the metal strip constituting the gage, it will be apparent that the gage can be economically produced.

The true cylindrical form of the handle is also preserved and by projecting the thread guide formed by the edges 5 within the hollow handle, the latter is left with a practically smooth exterior devoid of projections and the like.

The operation is similar to the patent in question, namely the thread is first passed through the eye and then laid over the slit 4, as depicted in full lines in Fig. 1, following which the thread is placed under tension to force same through the slot and past the edges 5, to lie within the needle interior as suggested in dotted lines in Fig. 1. The point is pushed through the cloth as shown in Fig. 6, to a predetermined degree controlled by the adjustment of the gage, the foot or end 8 of which latter by engaging the cloth arresting the extent of penetration as is now obvious.

It is particularly to be noted that the simplification of the present invention as compared with the patent aforementioned is marked; namely the lateral flanges of the patent which extend outwardly therefrom are entirely eliminated, and the gage structure is reduced to a simple strip-like part having similar out-turned ends and requires merely a pair of slight spring fingers to operatively relate the gage to the needle body.

What is claimed is:—

1. An embroidery needle composed of a hollow body, a shank and a point, the shank

and body having a longitudinal slot, said slot in the body of the needle being formed with inwardly turned side walls to form a thread receiving passage, in connection with the slot in the shank, and adapted to leave the handle periphery smooth.

2. An embroidery needle composed of a hollow body, a shank and a point, the shank and body having a longitudinal slot, said slot in the body of the needle being formed

with inwardly turned side walls and in connection with the slot in the shank forming a thread receiving passage with the side walls in the body lying in converged relation to each other.

15

In testimony whereof we affix our signatures.

GEORGE V. PADE.
CONRAD T. NEITZEL.
